UNITED STATES PATENT OFFICE.

WILLIAM RITSCHARD, OF DETROIT, MICHIGAN.

PROVISION-CHOPPER.

1,031,873.

Specification of Letters Patent.

Patented July 9, 1912.

Application filed September 11, 1911. Serial No. 648,606.

To all whom it may concern:

Be it known that I, WILLIAM RITSCHARD, a citizen of the United States, residing at Detroit, in the county of Wayne and State 5 of Michigan, have invented a new and useful Provision-Chopper, of which the following is a specification.

The present invention relates more particularly to an instrument which is used to 10 slice and chop vegetables, fruits, victuals, etc.

The object of the present invention is to provide an instrument which can be used in the kitchen, dining table, or butcher shops, 15 for different purposes, though principally it is used for the slicing and chopping of vegetables and fruits, etc.

The preferred construction of the invention is illustrated in the accompanying 20 drawings, wherein:—

Figure 1 is a side view of the whole construction. Fig. 2 is a top view of the lower handle B, and knife C. Fig. 3 is a top view of the principal holding member M, comprising the handle A, the jaw 12, and the U-shaped guard 15. Fig. 4 is a perspective view of the U-shaped guard 15 in Fig. 3. Fig. 5 and Fig. 6 are two views of the adjustable steel plate guard 11.

Similar reference-numerals designate corresponding parts in all the figures of the drawings.

In the construction illustrated in Fig. 1, M is the principal holding member comprising the top handle A, the jaw 12 being mounted with an adjustable steel plate guard 11, and a U-shaped wire guard 15. The principal holding member M, being provided with an aperture in a long pivot 18, 35 to receive the pivoted cutting member B, with the knife C riveted thereto, and it is obviously seen that when A and B are pressed together, the knife C, and the jaw 12 will come together, thus cutting the different substances that are held in between. Furthermore, the top surface of the said 40 jaw 12, having a plurality of longitudinal grooves, which run from K to L, wherein the steel plate guard 11 can be adjustably 45 positioned. And in further operating the device to obtain the variable and desired thicknesses of the slices, the steel plate guard 11, having a sharp edge at E, is em-

ployed, by it being slipped on into the proper groove, which runs from K to L on 55 the top surface of the jaw 12, for by placing the guard 11, say, into the first groove to the knife, the thickness of the slices will be exactly the same as the space between the guard 11, and the said knife. 60

In making still further and accurate use of the instrument a U-shaped wire guard 15 is used, which is hooked on to the jaw 12, and is extending over and beyond the concaved recess 17, this guard 15 is used as a 65 rest, and to assist in the guiding of certain substances, and to keep the object to be sliced in a parallel and horizontal position, with the said knife, so that in holding the object with the left hand up against the two 70 guards, a two-way parallel slice will be obtained. And it will be understood that the instrument can be used to good advantage without making use of one or either of the two guards, 11 or 15. The groove 13 75 on the top surface of the jaw 12 is of considerable depth, and having a square edge, so that the said knife will shear the substances when it passes same edge.

The sloping concaved recess 17 is to give 80 clearance for objects of round form, and to permit access with the fingers to the knife. The pivot 18 and nut 29, are used in holding the pivoted member B to the principal holding member M. It is obviously 85 seen that in using the device, the two handles A and B are pressed together with the one hand, while the coil spring 20 in between the two handles, does the opening.

The coil spring 20 on the handle B is held 90 in position with a taper head screw passing through the two lugs 24.

From the foregoing, it is thought that the construction, operation and many advantages of the herein described invention will 95 be apparent to those skilled in the art, without further description.

Having thus described my invention, what I claim as new, and desire to secure by Letters Patent of the United States, is: 100

In an instrument of the class described, a holding member, comprising a handle, a pivoted intermediate portion and a jaw having a cutting edge, said jaw having a plurality of longitudinal grooves, and a concave recess, a guard mounted adjustably in 105

one of the longitudinal grooves, a U-shaped guard extending over and beyond said recess, and a coöperating cutting member pivoted to said holding member, at said pivotal portion thereof, and a spring engaging said holding and cutting members, substantially as shown and described.

In testimony that I claim the foregoing as my own, I have hereto affixed my signature in the presence of two witnesses.

WILLIAM RITSCHARD.

Witnesses:
